CLAIM

The ornamental design for a golf mat as shown and described.

DESCRIPTION

FIG. 1 is a perspective view of a golf mat, showing my new design;

FIG. 2 is a top, plan view thereof;

FIG. 3 is a bottom, plan view thereof;

FIG. 4 is a right, side elevation view thereof;

FIG. 5 is a left, side elevation view thereof;

FIG. 6 is a front elevation view thereof; and,

FIG. 7 is a rear elevation view thereof.

The perimeter broken lines show stitching and form no part of the claimed design. The broken lines showing logos illustrate portions of the golf mat and form no part of the claimed design.

1 Claim, 5 Drawing Sheets(56)
